Primary Examiner — Caron D Veynar*Assistant Examiner* — Martie K Holtje(74) *Attorney, Agent, or Firm* — James E. Howard; Andre Pallapies(57) **CLAIM**

The ornamental design for a kitchen ventilator, as shown and described.

DESCRIPTION

FIG. 1 is a bottom perspective view of a kitchen ventilator according to my new ornamental design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines represent environment or structure and do not form any part of the claimed design.

The dotted lines in FIG. 4 delineate an opening and/or indicate the border between claimed, exterior subject matter and unclaimed, interior feature(s), and do not form any part of the claimed design.
